Fempto Satellites by Nasa. Principal Investigator listed as applicant: Andrew Filo. publication not dated. expedition duration reference photos dated Sep. 2017-Feb. 2018. found online [Aug. 21, 2020] https://www.nasa.gov/mission_pages/station/research/experiments/explorer/Investigation.html?id=7637.*

Primary Examiner — Marissa J Cash

(57) **CLAIM**

The ornamental design for a fempto satellite, as shown.

DESCRIPTION

FIG. 1 is an isometric view of the fempto satellite showing my new design;

FIG. 2 is a top view thereof;

FIG. 3 is a bottom view thereof;

FIG. 4 is a back view thereof; and,

FIG. 5 is a front view thereof.
